UNITED STATES PATENT OFFICE.

CHARLES E. MILLER, OF LAUREL, MISSISSIPPI, ASSIGNOR OF ONE-HALF TO CHARLES GREEN, OF LAUREL, MISSISSIPPI.

MEANS FOR OPERATING RAILWAY-CROSSING GATES.

Application filed August 8, 1927. Serial No. 211,397.

This invention relates to means for automatically operating railway crossing gates. The invention comprises means whereby when a train is approaching a crossing, 5 protected by a gate, the car wheels will engage gate-closing mechanism at a distance from the crossing, and this mechanism will operate to close the gate. If the train, after passing the gate-closing 10 means, continues over the road crossing, the wheels will operate gate releasing devices and the gate will automatically open. At certain crossings, as where switching occurs, a train may approach a crossing and cause 15 the gate to close and then back before reaching the crossing. The invention comprises means whereby if a train, after causing the closure of the gate, moves backward before reaching the crossing, the gate will be automatically opened by the reversed movement 20 of the train.

In the accompanying drawing,

Fig. 1 is a plan view of the gate-operating mechanism arranged adjacent a railway 25 track, parts being broken away;

Fig. 2 is a side elevation of the same;

Fig. 3 is a plan view of the operating mechanism on a larger scale than in Fig. 1, the gate and latch being omitted;

30 Fig. 4 is a section on the line 4—4 of Fig. 3;

Fig. 5 is a section on the line 5—5 of Fig. 3;

Fig. 6 is a side elevation of the latch, 35 looking from right to left in Figs. 1 and 2; and,

Fig. 7 is a section on the line 7—7 of Fig. 6, showing the lever for operating the latch.

Referring to the drawing, *a* represents a 40 railway track, *b* represents a roadway crossing the track, *c* indicates a gate pivotally mounted at one side of the roadway and adapted to swing downwardly across the same, and *d* indicates a latch arranged at 45 the opposite side of the roadway and adapted to hold the gate when the latter is brought to the horizontal position across the roadway.

As shown, the gate comprises a long arm 50 1, pivotally mounted near one end upon a pedestal 2 and having a bar 3 projecting at an angle to the arm below its pivotal point, said bar carrying a weight 4 which holds the arm normally in upright position, as shown 55 in full lines in Fig. 2. The latch, as shown

in Fig. 6, comprises an upright bar 5, secured in a fixed position at one side of the track, and a bar 6 pivotally connected at 7 to the lower end of the bar 5, the bar 6 having an arm 6^a which extends close to the track and 60 has a part 6^b projecting above the track rail *r* and adapted to be engaged by the flanges of the car wheels passing along the rail.

The upper ends 5^c and 6^c of the bars are 65 turned outwardly in opposite directions to form guides for the free end of the gate, and the bar 6 is curved as shown at 6^d to engage and hold the gate, the free end of which is indicated in dotted lines in Fig. 6. A spring 6^e presses upwardly against the 70 arm 6^a and normally holds the latch closed. A bell crank lever 9, pivoted in a support 10, has a forked arm 9^a which straddles the arm 6^a of the latch, and the other arm 9^b of the bell crank lever projects downwardly 75 from its pivotal point and is connected by a cable 11 to a latch controlling device *e*, spaced a relatively long distance from the latch and at the other side of the road crossing.

The latch tripping device *e*, as shown in 80 Figs. 1, 3 and 5, comprises a short shaft 12, which is arranged at right angles to the rail *r* in bearings 13 and 14 on a base-piece 15. A lug 16 projects upwardly from the end of 85 the shaft next the rail and a cam 17 projects laterally from this lug, this cam curving or inclining away from the side of the rail and in the direction away from the road crossing and gate. A spring 18 presses the shaft 90 endwise toward the rail and a spring 19 tends to turn the shaft and hold it in the position shown with the lug 16 projecting upwardly and a stop 20 on the shaft resting against the base 15.

With the construction described, the side 95 of a car wheel *s*, Fig. 1, moving in the direction of the arrow, toward the road crossing, will engage the cam 17 of the tripping device and press the shaft 12 away from the rail without turning the shaft, and the tread of the wheel will pass the lug 16, but after the wheel has passed the tripping device, if its direction of motion should be reversed, the tread of the wheel will engage the lug 16 100 and press it to the left, thus rocking the shaft 12 against the tension of the spring 19. As the cable 11 is secured to the shaft, this rotary movement of the shaft will cause the cable to be pulled to the left and the bell 105 110

crank lever 9 will be rocked, causing the arm 6 of the latch to rock into position to release the gate.

It will be evident from the foregoing, that 5 a car wheel traveling in the direction of the arrow, Fig. 1, will not trip the gate latch in passing the tripping device *e*, but will trip the latch after said wheel has passed over the crossing and depressed the arm 6^a of the latch. It will also be evident that if the car wheel, after having passed the tripping device *e* and before reaching the crossing and latch arm 6^b, is stopped and backed past 10 the tripping device *e*, it will operate the latter to trip the latch.

In conjunction with the latch releasing mechanism just described, I provide means, indicated at *f*, for automatically closing the gate when a train is approaching the road crossing. This mechanism comprises a plurality of ratchet levers 21, centrally pivoted upon a bar 22, these levers being arranged at right angles to the track and each having at its outer end a spring pawl 23 and at its 25 inner end, adjacent the track, an upward projection 21^a which extends slightly above the rail *r* and is adapted to be engaged and depressed by the treads of the car wheels. These levers are spaced suitable distances 30 apart and independently pivoted upon the bar 22, and a spring 24 is arranged under each lever to raise the end of the lever next the rail and depress the opposite end carrying the pawl. The pawls engage corresponding ratchet wheels 25, which are keyed to a shaft 26, upon which is also secured a clutch member 27. A winding drum 28, journaled upon the shaft 26, is normally held in engagement with the clutch member by a spring 29, which is coiled about the shaft. A grooved collar 30, surrounding the shaft and secured to the drum, is engaged by a clutch lever 31, which is centrally pivoted upon a suitable supporting member 32. A 45 pivoted arm 33 extends over the free end of the clutch lever and is yieldingly held against the lever by a spring 34. This arm has a bend 33^a, near its free end, which holds the lever in or out of the clutching position, according to whether or not the end of the lever is at one side or the other of this bend. Normally the clutch lever is held in the clutching position, as shown in Figs. 1 and 3, so that when a car wheel passes over 50 the inner ends of the ratchet levers 21, these levers, through the pawls and ratchet wheels, will operate successively to turn the shaft 26 and the winding drum. A bell crank lever *g* is pivotally mounted adjacent the clutch lever, and a cable 35, attached to the drum, is secured to one arm 36 of this bell crank lever, this cable extending over a curved guide 37, attached to said arm. The other arm 38 of the bell crank lever is connected by a cable 39, which extends through

a pipe 40, to a short crank arm 41, attached to the gate 1 at its pivotal point. The bell crank *g* carries on the arm 36 a tappet 42, adapted to engage one side of the clutch lever and move it into the clutching position, and on the arm 38 a tappet 43, adapted to engage the clutch lever and move it to clutch-disengaging position.

The operation of the mechanism is as follows: Assuming that a train is moving in 75 the direction of the arrow, Fig. 1, toward the road crossing *b*, and that the gate is open, as the wheels pass over the tripping device *e*, they will engage the cam 17 and move the shaft 12 endwise without turning 80 it about its axis, therefore, no pull will be exerted on the cable 11. As the train progresses, its wheels will rock the several levers 21, thereby rotating the winding drum, the cable on which will rock the bell crank 85 lever *g* to the left until the tappet 43 on said lever strikes the clutch lever and moves the latter into position to disengage the drum from the clutch member 27. At this time, the free end of the clutch lever will have 90 passed to the left of the bend 33^a on the spring pressed arm 33, and the lever will thereby be held out of clutch-engaging position. When the bell crank lever is thus 95 rocked, it causes the cable 39 to pull the gate to its horizontal position, across the roadway, and the latch member *d* then holds the gate closed. As the train passes over the road crossing, its wheels depress the arm 100 6^a of the latch member, thereby rocking said member to release the gate, which is automatically returned to its open position by the weight 4. In moving to its open position, the arm 41 on the gate pulls upon the cable 39 and this causes the bell crank lever 105 *g* to rock to the position shown in Figs. 1 and 3, and to unwind the cable 35 from the drum. Near the end of the movement of the bell crank, the stop 42 thereon strikes the clutch lever and moves it into the clutch- 110 engaging position, permitting the spring 29 to move the winding drum into engagement with the clutch member 27, so that the apparatus is then set for the next train.

After a train has passed over the gate-closing mechanism *f* and caused the gate to close, it may often be necessary, as in switching operations, to stop and back the train before it reaches the road-crossing, in which case it is desirable to provide means for automatically opening the gate. This is accomplished in the present invention, by the engagement of the wheels with the lugs 16 on the tripping device *e*, which causes the shaft 12 to rock in the direction to pull the cable 11, which rocks the bell crank *g*, and the latter rocks the latch arm 6 to release the gate, which is immediately returned to its upright or open position by the weight 4.

What I claim is:

1. The combination with a railway track, of a road-crossing gate, means for moving the gate to open position, means for closing the gate comprising a shaft having a plurality of ratchet wheels and a clutch member secured thereto, a plurality of ratchet levers engaging said wheels and adapted to be rocked in succession by a car wheel on the track, a winding drum normally engaging said clutch member, a clutch lever for releasing the drum from the clutch member, a pivoted tappet member for moving said lever to release and engage the drum with the clutch member, a cable connecting the drum with the tappet member and a cable connecting the latter with the gate, a latch for holding the gate closed, and means operated by a car wheel to release the latch.
2. The combination with a railway track, of a road-crossing gate, means for moving

the gate to open position, means for closing the gate comprising a shaft having a plurality of ratchet wheels and a clutch member operable thereby, a plurality of ratchet levers engaging said wheels and adapted to be rocked in succession by a car wheel on the track, a winding drum normally engaging said clutch member, a clutch lever for releasing the drum from the clutch member, a cable connected to the drum and connections between said cable and the gate for moving the latter, said connections including a member adapted to release and engage the drum with the clutch member, a latch for holding the gate closed, and means operated by a car-wheel to release the latch.

In testimony whereof I hereunto affix my signature.

CHAS. E. MILLER.
